[57] CLAIM

The ornamental design for a transport crate, as shown
 and described.

DESCRIPTION

FIG. 1 is a top perspective view of a transport crate
 showing my new design;

FIG. 2 is a bottom perspective view of the transport
 crate shown in FIG. 1 illustrating the sides not shown in
 FIG. 1;

FIG. 3 is a top perspective view of a second embodiment
 of the transport crate;

FIG. 4 is a bottom perspective view of the transport
 crate shown in FIG. 3 illustrating the sides not shown in
 FIG. 3;

FIG. 5 is a top perspective view of a third embodiment
 of the transport crate; and,

FIG. 6 is a bottom perspective view of the transport
 crate shown in FIG. 5 illustrating the sides not shown in
 FIG. 5.
